UNITED STATES PATENT OFFICE.

GEORGE W. BUSS, OF WOBURN, MASSACHUSETTS.

FOLDING STEP-LADDER.

No. 811,616.

Specification of Letters Patent.

Patented Feb. 6, 1906.

Application filed July 17, 1905. Serial No. 269,979.

To all whom it may concern:

Be it known that I, GEORGE W. BUSS, a citizen of the United States, residing at Woburn, county of Middlesex, and State of Massachusetts, have invented an Improvement in Folding Step-Ladders, of which the following description, in connection with the accompanying drawings, is a specification, like numerals on the drawings representing like parts.

This invention has for its object to provide a novel folding step-ladder in which the framework supporting the tread folds as well as the legs or braces. The framework of my step-ladder comprises two stiles, which preferably are inclined toward each other and each of which is pivoted at its upper end to the top tread or cap-piece, and a plurality of treads which may be of different lengths, which are pivotally connected to one stile and are slidably connected to the other stile. With this construction the two stiles of the ladder may be folded together, thus condensing the step-ladder into a minimum space.

The particular features wherein my invention resides will be more fully hereinafter described and then pointed out in the claims.

In the drawings, Figure 1 is a section taken just inside the outer members of the stile. Fig. 2 is a side view. Fig. 3 is an edge view showing the ladder folded, and Fig. 4 is a bottom plan view of Fig. 3.

The ladder comprises two stiles or side pieces which support between them the treads 3 and the cap-piece or top step 4. Each stile is shown as comprising two members 5, which are connected by tread-supports, herein shown as rods or rungs 6, and also preferably by suitable cross-pieces 7, the function of which will be explained more fully herein-after. The treads 3 are supported upon the rods 6. Each tread is pivoted at one end to a rod 6 of one stile and rests on and has sliding engagement with a rod 6 of the other stile. The side pieces or stiles are shown as converging toward the top of the ladder, and therefore the treads 3 are of different lengths, the lowest tread being the longest and the upper tread the shortest; but this converging of the stiles is not essential to the invention.

In order to get the proper sliding movement between each tread and one of its tread-supporting rods 6, I prefer to provide each tread with a suitable slot, through which the rod extends. This slot may be made in any suitable way, and as herein shown it is

formed by a suitable guide-piece 8, which is secured to the under side of the tread and forms between it and the tread a runway for the corresponding rod 6 to slide in. The upper end of each stile is pivoted to the cap-piece 4. With this construction it will be seen that the ladder can be folded, as shown in Fig. 3, by merely swinging the right-hand side piece or stile in Fig. 1 upwardly with relation to the other and toward the other, the treads 3 sliding on the rods 6 of the left-hand stile, Fig. 1, during such folding operation.

Where the stiles of the ladder converge at the top, so that the treads are of different lengths, it is necessary to provide this sliding connection between the treads and one of the stiles in order that the ladder may be folded, as described.

It will be noted from Fig. 2 that the treads and the tread-supporting rods do not stand perpendicular to the members 5 of the side pieces or stiles, and therefore when the ladder is folded said treads have the angular relation to the tread-supporting rods shown in Fig. 4. To permit this twisting or angular movement, I have pivoted the treads to the rods of one stile by means of eyes or staples 9, which permit the necessary turning or twisting movement of the treads with relation to the rods 6. I prefer also to pivot the stiles to the cap-piece 4 in the same manner.

In order to hold the ladder firm when it is opened ready for use, as shown in Figs. 1 and 2, I employ suitable toggle-lever or knuckle-joint braces 10, which are pivoted to the two stiles and which when straightened, as shown in Fig. 1, firmly hold the stiles separated. To further brace the structure and make it a rigid one when unfolded, I employ the cross-pieces or cleats 7 on the left-hand stile, Fig. 1, said cross-pieces being so positioned that when the ladder is fully open the extremities of the treads are brought hard against the under side of the cross-pieces by the turning movement of the treads about the tread-supports 6 of the left-hand stile, said treads being firmly held in this position by the braces 10. The combined action of the braces and the lever purchase which is thus obtained on the treads makes the ladder extremely firm. The loops or guides 8 are also so positioned that when the ladder is open and the braces 10 straightened, as shown in Fig. 1, the rods 6 are forced hard against the ends of the guides, as seen best in Fig. 1. I have also provided certain of the treads with ears 11, which hook

over the cleats 7 on the right-hand stile, Fig. 1, when the ladder is unfolded and in condition for use, said ears serving in connection with the guides 10 to assist in holding the structure firmly in its open position.

13 designates legs or braces for supporting the ladder in its upright position. I propose to hinge one leg to the upper end of each stile, as at 14, and to connect each leg with a corresponding stile by means of a toggle or knuckle jointed brace 15.

The two legs 13 are connected together by means of a similar brace 16. In folding the ladder the first step is to buckle the braces 15 and fold the legs against the stiles. The braces 10 and 16 are then buckled and the right-hand stile, Fig. 1, moved upwardly with relation to the left-hand stile and toward the latter. As a result the ladder folds together 20 transversely, as shown in Fig. 3, and when folded it occupies a minimum space. The construction is such that when the ladder is unfolded or opened out, as shown in Figs. 1 and 2, it is firmly braced and is very rigid.

25 I have shown the lower tread as provided with a gain 17, which fits the under side of the lower cross-piece 7, and thereby assists in holding the structure rigid.

While I have herein shown one simple way 30 of locking the stiles in their open position—to wit, the braces 10—yet my invention is not necessarily limited to this structure, as any appropriate locking device may be used.

One of the important features of my invention is the pivoting of the treads to one stile 35 and providing a sliding connection between said treads and the other stile, thereby permitting treads of different lengths to be used, and another important feature is the provision of the cleats 7, against which the ends of 40 the treads are firmly held by the opening movement of the ladder, whereby the ladder is made very stiff and rigid.

Having fully described my invention, what 45 I claim as new, and desire to secure by Letters Patent, is—

1. In a folding step-ladder, a pair of stiles, each comprising two members, tread-supports connecting said members, and a series 50 of treads pivoted to the tread-supports of one stile and having a sliding engagement with those of the other stile.

2. In a folding step-ladder, a pair of stiles each comprising two members, tread-supports connecting said members, a series of 55 treads of different lengths pivoted to the tread-supports of one stile and having a slid-

ing engagement with those of the other stile, and a cap-piece of less length than the shortest tread pivoted to the upper end of each 60 stile.

3. In a folding step-ladder, a pair of stiles each having a plurality of tread-supports, a series of treads, each tread pivoted at one end to a tread-support of one stile and resting at 65 the other end on a tread-support of the other stile, and cleats on said latter stile to engage the upper side of the treads as the ladder is opened.

4. In a folding step-ladder, a pair of stiles, 70 a plurality of treads of different length, each tread being pivoted to one stile and having a sliding pivotal connection with the other stile, and a cleat on the latter stile to engage the upper side of the extreme end of each 75 tread as the ladder is opened.

5. In a folding step-ladder, a pair of stiles, each comprising two members connected by tread-supports, a series of treads pivoted to the tread-supports of one stile and having 80 a sliding engagement with those of the other stile, and cross-pieces connecting the members of the latter stile and arranged to be engaged by the upper side of the treads when the ladder is open for use. 85

6. In a folding step-ladder, a pair of stiles, each comprising two members connected by tread-supporting rods, a series of treads, each tread pivoted at one end to a rod of one stile and resting at the other end on a rod of the 90 other stile and a guide secured to each tread and embracing the corresponding rod of the latter stile.

7. In a folding step-ladder, a pair of stiles each comprising two members connected by 95 tread-supports, a series of treads pivoted to the tread-supports of one stile and slidably connected to the tread-supports of the other stile, and jointed braces connecting the stiles.

8. In a folding step-ladder, a pair of stiles 100 each comprising two members connected by tread-supports, a series of treads pivoted to the tread-supports of one stile and slidably connected to the tread-supports of the other stile, jointed braces connecting the stiles, and means to limit the spreading movement of the stiles caused by straightening the braces. 105

In testimony whereof I have signed my name to this specification in the presence of two subscribing witnesses.

GEORGE W. BUSS.
